UNITED STATES PATENT OFFICE.

EDWARD S. SMITH, OF AKRON, OHIO, ASSIGNOR OF ONE-THIRD TO JOHN A. CHRISTIE,
OF AKRON, OHIO.

GARMENT.

1,295,625.

Specification of Letters Patent. Patented Feb. 25, 1919.

Application filed March 22, 1918. Serial No. 223,989.

To all whom it may concern:

Be it known that I, EDWARD S. SMITH, a citizen of the United States, residing at Akron, in the county of Summit and State 5 of Ohio, have invented new and useful Improvements in Garments, of which the following is a specification.

This invention has relation to improvements in the cuff portions of such garments 10 as shirts. Briefly, the greatest wear in connection with the use of such garments as shirts is on the cuffs due to the frequent soiling, and consequently repeated laundrying thereof and as the wearing out of the cuff 15 portions renders the future use of the garment substantially useless, it is the object of this invention to provide a garment having a binary or double cuff so arranged that when they are simultaneously used the face 20 of one of the members only is exposed to wear and soiling, provision being made to permit the infolding and temporary holding of the used or soiled portion within the sleeve while permitting the full and free use 25 of the unused companion member as desired.

In other words the invention contemplates a garment provided with two cuffs substantially alike and normally adapted to nest or lie one within the other and similar in all 30 respects, and so arranged that when ordinarily used the inner cuff is folded back over the outer cuff, and when the inner cuff which receives the wear or is soiled it is folded inwardly against the inside of the sleeve and 35 there fastened permitting the use of the outer cuff in the usual manner and by this means prolonging the life of the shirt or garment by reducing the number of times that laundrying of the garment is required 40 and enabling the user to wear the garment longer without relaundrying.

With the foregoing and other objects in view, the invention consists in the novel construction, combination and arrangement of 45 parts constituting the invention to be hereinafter specifically described and illustrated in the accompanying drawings which form a part hereof wherein is shown the preferred embodiment of the invention, but it is to be 50 understood that changes, variations and modifications can be resorted to which come within the scope of the matter hereinafter claimed.

In the drawings in which similar refer-

ence numerals indicate like parts in the different figures, 55

Figure 1 is a perspective view of a portion of the sleeve of a garment provided with a pair of cuffs embodying the present invention showing the cuffs in their inoperative or open position.

Fig. 2 is a view similar to Fig. 1 with the cuffs folded back in their initial operative position, and

Fig. 3 is a view similar to Figs. 1 and 2 65 showing the outer cuff in its operative position and the inner cuff in its infolded and inoperative position.

Referring to the drawings in detail the reference numeral 1 denotes the end of the 70 sleeve of some garment such as a shirt to which cuffs are customarily attached and provided with the usual slit 2. This sleeve is furthermore provided on its inner faces with holding means such as buttons 3 and 4. 75 Secured to or formed integral with the end of the sleeve 1 are a pair of cuffs 5 and 6 the cuff 5 being disposed outwardly of the cuff 6 and as both of the cuffs are practically similarly formed and fashioned they nest 80 one within the other and lie in contacting engagement when in their open or expanded position as shown in Fig. 1. The members 5 and 6 are provided with the usual button holes 7 and 8 to receive ordinary cuff buttons employed for holding the cuffs of garments of this description. The members 5 and 6 may be formed integral with the sleeve 1 or may be secured thereto by 85 stitches 9 but the mode or manner of connecting the cuffs with the end of the sleeves is immaterial to this invention. In ordinary practice the two members 5 and 6 will initially be folded back in unison and simultaneously as shown in Fig. 2 to permit the 90 positioning of a cuff button through the registering openings 7 and 8 for holding the cuff in shape as is the usual practice thereby causing the inner face of the inner cuff 6 to 95 form the outer or wear resisting portions of the entire cuff unit when in use. When soiled or worn the inner cuff 6 is bent back or infolded flatwise against the inner face of the sleeve and there held in place by interengaging the buttons 3 and 4 with the 100 button holes 8 as shown in Fig. 3. When thus arranged the inner face of the outer cuff 5 presents a clean and unsmeared surface

for use and when both cuff members 5 and 6 have become soiled the garment is then ready for laundrying.

I claim:

- 5 1. In combination with a sleeve, a pair of similar double length cuffs foldable centrally of their length outwardly and backwardly to an operative position and having their inner edges connected to the free end edge of the sleeve to normally extend lengthwise therefrom and be alternately used, said cuffs being disposed one within the other and unconnected with each other except at their point of connection to the free end edge of the sleeve, and fastening means for temporarily holding the inner cuff within the sleeve when not in use, substantially as described.
- 10 2. In combination with a sleeve, a pair of similar double length cuffs foldable centrally of their length outwardly and backwardly to an operative position and having their inner edges connected to the free end edge of the sleeve to normally extend lengthwise therefrom and be alternately used, said cuffs being disposed one within the other and unconnected with each other except at their
- 15 20 25

point of connection to the free end edge of the sleeve, and fastening means for temporarily holding the inner cuff at full length 30 flatly against the inner face of the sleeve when said inner cuff is not in use, substantially as described.

3. In combination with a sleeve, a pair of similar double length cuffs foldable centrally of their length outwardly and backwardly to an operative position and having their inner edges connected to the free end edge of the sleeve to normally extend lengthwise therefrom and be alternately used, said 35 40 45 50 cuffs being each provided with a set of button-holes and being disposed one within the other and unconnected with each other, except at their point of connection to the free end edge of the sleeve, and buttons within said sleeve and engageable in the button-holes of the inner cuff to temporarily hold the latter at full length flatly against the inner face of the sleeve when said inner cuff is not in use, substantially as described.

In testimony whereof I have hereunto set my hand.

EDWARD S. SMITH.
